CLAIM

The ornamental design for a shave preparation container lid, as shown and described.

DESCRIPTION

FIG. 1 is a top plan view of a shave preparation container lid; FIG. 2 is a bottom plan view thereof, showing a mirrored surface on the inside of the lid;

FIG. 3 is a side elevation cross-sectional view, taken through line 3-3 of FIG. 1, showing the mirrored surface from the side;

FIG. 4 is a top plan view of another shave preparation container lid of this invention, showing a mirrored surface on the top of the lid;

FIG. 5 is a bottom plan view thereof; and,

FIG. 6 is a side elevation cross-sectional view, taken through line 6-6 of FIG. 5, showing the mirrored surface from the side.

In the drawings, the broken lines show portions of a shave preparation container lid that form no part of the Claim.
